United States Patent

Des. 242,170
Patented Nov. 2, 1976

242,170

MOVIE PROJECTOR

Takaharu Kato, Tokyo, Japan, assignor to
Kabushiki Kaisha Ricoh

Filed July 5, 1974, Ser. No. 486,055

Term of patent 7 years

Int. Cl. D16—04

U.S. Cl. D16—23

FIG. 1

FIG. 2

FIG. 3

FIG. 4

FIG. 5

FIG. 6

FIG. 7

FIG. 1 is a front, top and left side perspective view of a movie projector showing my new design;
 FIG. 2 is a front elevational view thereof;
 FIG. 3 is a rear elevational view thereof;
 FIG. 4 is a right side elevational view thereof;
 FIG. 5 is a left side elevational view thereof;
 FIG. 6 is a top plan view thereof; and
 FIG. 7 is a bottom plan view thereof.
 I claim:

The ornamental design for a movie projector, substantially as shown.
